US00D913779S

(12) **United States Design Patent** (10) **Patent No.:** **US D913,779 S**
(45) **Date of Patent:** **** Mar. 23, 2021**

(54) **STORAGE RACK GUARD DROP-IN
BRACKET DEVICE**

(71) Applicant: **SpaceGuard Products, Inc.**, Seymour, IN (US)

(72) Inventors: **Edward M. Murphy**, Pittsburgh, PA (US); **Scott A. Jump**, North Vernon, IN (US); **Christopher Lee Roberts**, Seymour, IN (US)

(73) Assignee: **SpaceGuard Products, Inc.**, Seymour, IN (US)

(**) Term: **15 Years**

(21) Appl. No.: **29/588,872**

(22) Filed: **Dec. 23, 2016**

(51) LOC (13) Cl. **08-05**

(52) U.S. Cl. **D8/381**

(58) **Field of Classification Search**

(57) **CLAIM**

The ornamental design for a storage rack guard drop-in bracket device, as shown.

DESCRIPTION

FIG. 1 is a front perspective view of our new design; FIG. 2 is a rear perspective view of our new design; FIG. 3 is a rear side view of our new design; FIG. 4 is a front side view of our new design; FIG. 5 is a second front perspective view of our new design; FIG. 6 is a front perspective view of our new design provided in relation to a bracket lock pin environment; FIG. 7 is a front perspective view of our new design; FIG. 8 is a rear perspective view of our new design; FIG. 9 is a rear side view of our new design; FIG. 10 is a front side view of our new design; FIG. 11 is a second front perspective view of our new design; FIG. 12 is a front perspective view of our new design in relation to a bracket lock pin environment;

FIG. 13 is a front perspective view of our new design; and, FIG. 14 is a second front perspective view of our new design in relation to a bracket lock pin environment.

The broken lines in the drawings illustrate portions of the storage rack guard drop-in bracket device which form no part of the claimed design.

1 Claim, 3 Drawing Sheets
